UNITED STATES PATENT OFFICE.

JOSEPH A. GROEBLI, OF NEW YORK, N. Y.

BEAD-SEWING MACHINE.

1,073,344.

Specification of Letters Patent. Patented Sept. 16, 1913.

Application filed October 5, 1912. Serial No. 724,025.

To all whom it may concern:

Be it known that I, JOSEPH A. GROEBLI, a citizen of the United States, and a resident of the city, county, and State of New York, have invented certain new and useful Improvements in Bead-Sewing Machines, of which the following is a specification.

My invention relates to a sewing machine adapted to attach small articles, such as beads, to a fabric.

Heretofore in attaching beads to a fabric, generally the beads were first strung upon a thread and then a second thread was wound spirally around the beads and the first thread, the purpose of the second thread being to retain the beads in proper position. This simply prepared the string of beads for attachment; and in this condition the string of beads was attached to a fabric by the use of a ziz-zag sewing machine, which latter secured the string of beads to a fabric, by forming stitches over the bead threads.

The object of my present invention is to construct a machine which will produce a more artistic and pleasing product, reduce and simplify the operation, and increase the speed of manufacturing as well as reduce the cost thereof. I accomplish these results

by making the machine for applying the beads to the fabric so that the beads may be attached by means of the thread on which they are strung, thereby avoiding the use of the second or spacing thread above referred to, as well as the separate sewing thread.

With my invention it is possible to produce a more artistic and pleasing product because the beads, or other articles of ornamentation, may be stitched upon the fabric by means of the thread upon which they are strung; and they may be secured to the fabric firmly, and in definite positions, so as not to move along their thread. Furthermore no thread engages over the exterior surface of the beads.

In the present machine stitches are formed with the bead thread, between the several beads. This is accomplished by means of a separator which operates between the thread looper and the stitching member (the needle), to separate or space the beads on their thread, so that they will be fed in proper relation to the stitching operations; and so that the stitching member may form stitches in the bead thread be-

tween the several beads. In the full embodiment of my invention the looper which casts the thread around the needle or stitching hook also moves the beads and their thread in such a way, relatively to the separator or bead feeder, as to cause a periodical separation or feeding of the beads, properly timed relatively to the stitching operations.

In Patent Number 1,041,780, dated October 22, 1912, I showed and described a machine for sewing beads onto fabrics and the present invention relates to a device of that character. In the present invention however, the machine is so constructed that the beads can not only be attached to the fabric in straight lines, but also in the form of curves or angles. That is to say, the fabric may be fed in any desired direction while the beads are being attached thereto. For this purpose the separator or bead feeder is made to move in the desired direction and to any desired extent to accomplish the feeding of the beads, while the looper and sewing hook are subject to a universal movement; which may be under hand control. Likewise the presser foot or fabric feeder is subject to a universal feeding movement.

In the drawings forming a part of this application; Figure 1 is a longitudinal elevation of a sewing machine embodying my invention in the preferred form, wherein portions of the casing are broken away to show the operating mechanisms more clearly, Fig. 2 is a rear elevation of a portion thereof, showing, on a larger scale, a portion of the stitching devices; Fig. 3 is an end view of a portion of Fig. 2, Fig. 4 is a sectional view taken on the line 4—4 of Fig. 2; Fig. 5 is a cross section showing the details of one form of looper which may be employed in the present combinations; Fig. 6 is a sectional view, taken on the line 6—6 of Fig. 1, looking in the direction of the arrows, and showing one form of device for operating the needle shaft, Fig. 7 is a face view of the cam block which appears in Fig. 6, Fig. 8 is a plan view of the bead separator or bead feeder, Fig. 9 is a sectional view thereof, taken on the line 9—9 of Fig. 8, Fig. 10 is an inverted plan view of the separator, Fig. 11 is a plan view of the support of the separator, Fig. 12 is a sectional view, taken on the line 12—12 of Fig. 1.

I have shown herein a complete sewing

machine embodying my invention in what I believe to be a very practical construction, but it is to be understood that my invention is not limited to the precise construction 5 which I will hereinafter describe.

The various devices are shown mounted on an ordinary framework 1, and upon a bed plate 2. The operating force for the several devices is here shown as being distributed from a main shaft 3 which is operated in any usual manner; and from a secondary shaft 4 which is operated from the main shaft by means of a belt 5 which travels over pulleys 6, 7, on the main and 10 secondary shafts. The pulleys 6, 7, are provided with pins 8 which engage in apertures 9 in the belt so that there will be no relative slipping between the belt and pulleys.

The stitching member in the present case 20 preferably consists of a needle or hook 10, and it is preferably arranged with its operating mechanism below the bed plate 2. The needle or hook 10 is carried by a reciprocating needle shaft 11 which is guided in 25 journals 12, arranged below the bed 2; which shaft may be reciprocated and rotated in the journals. On the shaft 4 there is a disk 13 which has a pin 14 that travels in the groove of a cam block 15 (see Figs. 1, 30 6 and 7). The cam block 15 reciprocates in the grooves 16 of a supporting bracket 17 carried upon a depending standard 18. Carried on the cam block there is a sleeve 19 which surrounds the needle shaft 11 but is 35 loose thereon to permit the needle shaft to revolve in the sleeve. Collars 20 are secured upon the needle shaft, and are arranged above and below the sleeve 19. As the shaft 4 revolves, the pin 14 which is arranged off 40 the center of the shaft, will reciprocate the block 15 up and down, but not laterally, owing to the shape of the cam groove 21. The reciprocation of the cam block will operate to reciprocate the needle shaft in its 45 bearings, to cause the needle or sewing hook to perform its stitching operations.

The looper for casting loops around the sewing hook or needle, is preferably arranged above the bed 2. The looper may 50 be variously constructed, but I prefer to use a looper consisting of a threaded body 22 revolving freely in a supporting casing 23 and held in position by collars 24. In addition thereto the looper preferably consists of a 55 tubular portion 25 extending outwardly and downwardly. The string of beads 26 travels downwardly through the looper and out of the tubular end 25 thereof. The looper body is free to rotate in its supporting casing; 60 and in order to rotate the same there is a worm or screw 27 arranged to reciprocate and also to revolve in the casing 23, at right angles to the looper body. The thread of the worm 27 meshes with the thread on the 65 looper body 22; and it is adapted to rotate

the looper when the worm 27 is reciprocated, or revolved, or when both reciprocated and revolved. The worm or screw 27 is carried upon a shaft 28 which is journaled in the machine frame and which may be reciprocated and revolved. One end of the shaft 28 is connected with one arm 29 of a lever which rocks on a fulcrum 30, by a connection which permits the shaft to revolve relatively to the arm. The other arm 70 31 of this lever is fulcrumed to a rod 32; and the latter is reciprocated by means of an eccentric 33 and strap 34. These connections serve to reciprocate the shaft 28 at each stitch operation of the machine, and 75 they permit a simultaneous rotative movement to be imparted to shaft 28.

To feed the fabric for the stitching operations I preferably employ a feeder and presser consisting of an annular ring 35 supported by an arm 36, over the bed 2, so as to encircle the path of the needle. The device which I prefer to employ for operating the feeder is as follows: A shaft 37 is supported over the sewing devices in 80 brackets 38 connecting with the head 39 of the machine. Upon this shaft is arranged a sleeve 40 having a groove provided with a cam surface 41 (see Fig. 1). The sleeve is loose on shaft 37 and it is 85 adapted to reciprocate on the same and to revolve around with it. A plate 42, sliding in a socket in the head of the machine frame, carries an arm 43 which partly encircles the sleeve 40 between the shoulders 90 44 thereof, whereby the sleeve 40 may revolve relatively to the plate 42 but is reciprocated by the latter. To the inner side of the frame head 39 is fulcrumed at 45, a lever 46; and one arm 47 thereof engages 95 with a cam 48 on the main shaft while the other arm 49 thereof contacts with a projection 50 on plate 42. Through the cam and lever the plate 42 and therefore sleeve 40 are periodically reciprocated. A sleeve 100 51 is secured to shaft 37; adapted to rotate with it, as will be explained later. It is provided with a pawl 52, one end of which engages the cam surface 41 of sleeve 40. The other end thereof operates against the 105 action of a spring 53 to move the member 54 which surrounds a portion of sleeve 51 and which is secured to the arm 36 that carries the presser or feeder 35. The member 40 is movable along the shaft 37 but 110 both 40 and 51 are adapted to revolve with the latter. The arm 36 which carries the presser or feeder is fulcrumed to a block 55 and the latter is fulcrumed at 56 to a support 57; the fulcrums 55 and 56 being 115 at right angles to each other, whereby the arm 36 may be moved by the pawl 52 in any lateral direction. Traveling in a socket in the head 39 is another sliding plate 58 which carries the support 57 for 120 125 130

the feeder. An extension 59 extends through the head and is acted upon by one arm 60 of a lever fulcrumed at 61. (See Fig. 4.) The other arm 62 of this lever 5 contacts with a cam 63 on the main shaft 3. These parts operate to reciprocate the plate 58 and therefore the feeder 35, which is carried therewith. A spring 64 serves to return the plate 42 and keep the arm 47 in contact with cam 48. Likewise a spring 65 serves to return plate 58 and keep the arm 62 in contact with the cam 63. When the shaft 3 is revolved, the feeder 35 is moved up and down by means of cam 63, lever 62, 60 and plate 58. The cam 48, lever 49 and plate 42 reciprocate the sleeve 40, which causes the rocking of pawl 52 and lateral movement of the arm 36 which carries the feeder. The direction of this lateral motion will depend upon the position of the sleeves 40 and 51, and that is controlled by the hand feed device as will be hereinafter described.

In addition to the above parts I provide a 25 device for separating or feeding the beads in proper order to the stitching devices; and I prefer to arrange the same between the looper and the fabric so that the movement of the looper will coöperate therewith to cause the separation or feeding of the beads. The device for this purpose is shown in detail in Figs. 8, 9, 10 and 11. An annular plate 66 is provided on its rim with a gear 67. A bracket 68 is attached to an extension 35 of the frame and is formed of separate halves 69 attached to the extension. The ring portions 70 thereof surround the plate 66 and engage in a groove 71 thereof. The purpose of the bracket 69 is to support the 40 separator in position over the fabric in a manner which will permit the separator to be revolved. From the annular plate 66 extends inwardly a neck portion 72 which carries a plate 73. The outer edge of the 45 latter is preferably circular for a distance extending between, say, the points 74 and 75; and then turns inwardly between the points 75 and 76. On the under side of plate 73 is secured at the point 73^a a tongue 50 77 which curves downwardly from the plate 73 a distance corresponding to the length of beads to be used in the machine. The tongue 77 preferably extends downwardly from the point where it is secured to the 55 plate 73, an increasing distance. The outer edge of this tongue is preferably curved between the points 78, 75 in the same circle as the portion of the plate 73 between the points 74 and 75, so that the plate 73 and tongue 77 when viewed from above or below form almost a complete circle. From the point 75 the tongue curves inwardly to 79. The beads are strung loosely on their thread and the bead thread is fed in any desired 60 manner to and through the looper. It passes

from the end 25 of the latter to the fabric (to the last stitch formed thereon). At the commencement of a stitch the end 25 of the looper will be in position near the point 74 of the separator; and the lowermost bead on 70 the bead thread will lie against the top surface of plate 73. Upon a partial revolution of the looper, the bead thread will be carried around the edge of plate 73 with the thread in contact with the edge thereof and the 75 beads resting on the plate. When the looper has revolved part way around, the bead thread will loose contact with the edge of plate 73 at about the point 75; and it will commence to contact with the edge of the 80 tongue. When this occurs, the beads will move down on their thread until the lowermost one rests on the tongue 77 which is at a slightly lower level to plate 73. The looper will reach its extreme movement, in 85 this direction, when the thread is in contact with the tongue or near the neck 72. Just previous to the above movement of the looper, the needle or hook 10 was advanced through the fabric by means of the crank, 90 pin and cam block previously described. The looper therefore, in carrying the thread around the separator, also casts a loop of the thread around the needle, the needle or hook at that time extending through the 95 fabric and the aperture 73^a in plate 73. The needle will then immediately descend and its hook will carry the thread through the fabric, forming a stitch therein, with the bead thread. At about this time the looper 100 will be reversed in direction. It will now carry the bead thread around the separator in a reverse direction to the first movement. The lowermost bead rests on the tongue 77 during a portion of the return movement until the thread comes to about the point 75. Then the thread will change from contact 105 with the tongue to contact with the plate 73. The plate 73 will now come between the lowermost bead which was resting on the tongue, and the one above it. Upon continuation of the movement of the looper, the lowermost bead will ride off the tongue, and fall down its thread to the fabric where the last stitch was formed. The bead above it, 110 which was the second bead, now rests on the plate 73; while the thread contacts with the outer edge thereof. The looper will reach the extreme of its return movement near the point 74. This completes one stitching operation. The same operations will be repeated; and each time the looper oscillates back and forth around the separator it will 115 not only cast the loop around the needle or sewing hook, but it will cause a bead to be separated from those above it and to drop down to the fabric. The needle, or hook, will therefore form stitches with the bead thread, between the several beads. While the needle is in the fabric, the presser or 120

125 130

feeder 35 will be pressed upon the fabric by the action of the spring 65. When the needle moves out of the fabric, the feeder 35 will be moved laterally by the action of 5 cam 48, lever 49, plate 42, sleeve 40 and pawl 52. As soon as the lateral feed has taken place, the presser will be raised by cam 63, lever 60, etc., and after rising the feeder will be moved back idly and then 10 down upon the fabric for a second feeding operation.

I provide means for operating the presser or feeder, in any desired direction and to position the looper, the needle, and the separator, whereby a universal feeding of the fabric may be obtained, in order to secure the string of beads to the fabric in any desired direction. I provide a hand control 15 for operating the above in synchronism, whereby there will be no conflict in the operation of the several devices.

A vertical shaft 80 is provided with a hand crank 81 for turning it. On this shaft there is a miter gear 82 meshing with 20 a miter gear 83 on a shaft 84. The latter also has a miter gear 85 which meshes with a miter gear 86 on the needle shaft 11. The latter gear is connected to the needle shaft by a "feather", so that the needle shaft 25 may be reciprocated. The turning of the crank 81 will operate through shaft 80, gears 82, 83, shaft 84 and gears 85, 86, to revolve the needle shaft according to the direction in which the fabric is to be fed or 30 stitched. On the shaft 80 there is a miter gear 87 which meshes with a miter gear 88 on a shaft 89. The latter has a miter gear 90 which meshes with the gear teeth 67 on the separator or bead feeder. When the 35 crank 81 is operated to turn the needle shaft, the gears 87, 88, shaft 89 and gears 90, 67 will also operate to revolve the separator in accordance with the direction of feed of the fabric. On the shaft 80 there 40 is a miter gear 91 which meshes with a miter gear 92 on shaft 28 which operates the looper. When the crank 81 is operated to turn the needle shaft and separator, the gears 91, 92, will also cause the shaft 28 to 45 revolve. This will revolve the looper and the action may be simultaneous with the movement imparted to the looper by the reciprocation of the shaft 28. The gear 92 is connected with shaft 28 by a "feather" 50 so that the shaft may be reciprocated relatively to the gear, but be turned by the latter. On the upper end of shaft 80 there is a miter gear 93 which meshes with a miter gear 94 on a shaft 95. There is a miter 55 gear 96 on the latter, which meshes with a miter gear 97 on shaft 37. When the crank 81 is turned, the shaft 80, gears 93, 94, shaft 95 and gears 96, 97, will revolve shaft 60 37 and with the latter the sleeves 40, 51, will 65 revolve. Thus the pawl 52 will be brought

to any desired position to operate the arm 36 and feeder 35 in any desired lateral direction; to cause the fabric which is being stitched to be fed in any desired direction.

From the above it will be apparent that 70 the various sewing devices, including the bead separator or feeder, may be turned in the desired direction and to any desired extent to cause the beads to be sewed to the fabric straight, curved or angular, or any 75 variation thereof. All the devices are turned synchronously, so that they will always properly coöperate regardless of the direction of feed of the fabric.

Various changes in the mechanism and 80 the positions of the various devices may be made without departing from the spirit and scope of my invention.

Having described my invention, what I claim is—

1. In a bead sewing machine a looper arranged to cast loops, a hooked needle co-operating therewith to stitch the fabric, a bead separator with which said looper co-operates to cause the separation or feeding 90 of beads on the sewing thread whereby the beads will be fed in regular order relatively to the stitching operations of the looper and needle, and means for moving the said bead separator, whereby the same may be positioned to correspond with the feeding of the fabric in different directions during the stitching operation.

2. In a bead sewing machine a looper arranged to cast loops, a hooked needle co-operating therewith to stitch the fabric, a bead separator with which said looper co-operates to cause the separation or feeding of beads on the sewing thread and means for moving the said looper and bead separator whereby they 100 may be positioned to correspond with the feeding of the fabric in different directions 105 during the stitching operation.

3. In a bead sewing machine a looper arranged to cast loops, a hooked needle co-operating therewith to stitch the fabric, a bead separator for separating or feeding beads which are strung on the sewing thread, a fabric feeder, and means for operating the fabric feeder to feed the fabric in different 110 directions during the stitching operation and for operating the looper and bead separator to cause movement corresponding with the direction of the feed of the fabric by said fabric feeder.

4. In a bead sewing machine a looper arranged to cast loops, a hooked needle co-operating therewith to stitch the fabric, a bead separator for separating or feeding beads on the sewing thread, a fabric feeder, and 115 means for operating the fabric feeder, looper and bead separator in synchronism, whereby the fabric may be fed in different directions during the stitching operation and whereby the looper and bead separator may 120 125 125 130 135 140 145 150 155 160 165 170 175 180 185 190 195 196

be simultaneously positioned according to the direction of feed of the fabric.

5. In a bead sewing machine a looper arranged to cast loops, a hooked needle arranged to operate from the opposite side of the fabric from said looper and adapted to pierce the fabric and coöperate with the looper to stitch the fabric, a bead separator arranged between the looper and fabric, 10 adapted to separate or feed beads on the sewing thread, said looper coöoperating with the bead separator to cause the separation or feeding of the beads, and a fabric feeder, including an annular member arranged between the said separator and the fabric, through which the needle and thread are adapted to pass.

6. In a bead sewing machine a looper arranged to cast loops, a hooked needle co-20 operating therewith to stitch the fabric, a bead separator for separating or feeding beads on the sewing thread, a fabric feeder, and means for operating the fabric feeder, looper, needle and bead separator in syn-25 chronism, whereby the fabric may be fed in

different directions during the stitching operation and whereby the looper, needle and separator may be simultaneously positioned according to the direction of feed of the fabric.

30

7. In a bead sewing machine a looper, a hooked needle coöperating therewith to stitch the fabric, and a bead separator, arranged to coöperate with the looper whereby beads will be separated or fed on the 35 sewing thread in regular order relatively to the stitching operations of the machine, said separator comprising a rotatable annular member having teeth, an inwardly extending plate, and a tongue, said plate and tongue being arranged to cause the separation or feeding of the beads, and means operating on the teeth of said annular member to rotate the bead separator.

Signed in the city, county and State of 45
New York, this 4th day of October, 1912.

JOSEPH A. GROEBLI.
